US0D1101586S

(12) **United States Design Patent** (10) **Patent No.:** **US D1,101,586 S**
(45) **Date of Patent:** **** Nov. 11, 2025**

(54) **OPTICAL PICKUP DEVICE**

(71) Applicant: **DE SANGOSSE**, Pont-du-Casse (FR)

(72) Inventor: **Rémi Pabis**, St Vincent de Lamont Joie (FR)

(73) Assignee: **DE SANGOSSE**, Pont-du-Casse (FR)

(**) Term: **15 Years**

(21) Appl. No.: **29/759,472**

(22) Filed: **Nov. 23, 2020**

(30) **Foreign Application Priority Data**

May 22, 2020 (EM) 007960109

(51) **LOC (15) Cl.** **10-04**

(52) **U.S. Cl.** **D10/97**
USPC **D10/97**

(57) **CLAIM**

The ornamental design for an optical pickup device as shown and described.

DESCRIPTION

FIG. 1 is a right side view of the optical pickup device showing the new design;

FIG. 2 is a left side view of the optical pickup device shown in FIG. 1;

FIG. 3 is a front view of the optical pickup device shown in FIG. 1;

FIG. 4 is a back view of the optical pickup device shown in FIG. 1;

FIG. 5 is a top view of the optical pickup device shown in FIG. 1;

FIG. 6 is a bottom view of the optical pickup device shown in FIG. 1; and,

FIG. 7 is a perspective view of the optical pickup device shown in FIG. 1.

1 Claim, 7 Drawing Sheets
